Warren D. House,
Atto ATTORNEY

UNITED STATES PATENT OFFICE.

CLARK A. THARP, OF LEAVENWORTH, KANSAS.

BOOK

Application filed December 31, 1925. Serial No. 78,549.

To all whom it may concern:

Be it known that I, CLARK A. THARP, a citizen of the United States, and a resident of Leavenworth, in the county of Leavenworth and State of Kansas, have invented a certain new and useful Improvement in Books, of which the following is a specification.

My invention relates to improvements in books. It is particularly well adapted for use in note books, such as are used by stenographers.

One of the objects of my invention is to provide, in a book of the kind described, a novel memoranda leaf having a portion arranged to be swung to a position projecting outside the edges of the book, in a position for inscribing memoranda thereon without any considerable movement of the writing hand from the normal writing position, and arranged to be swung, when not in use, to a position wholly within the edges of the leaves of the book.

A further object of my invention is to provide, in a book of the kind described, two memoranda leaves of the kind referred to disposed adjacent to the covers respectively of the book, and arranged so that when the book is positioned for writing on one side of the leaves, one of the memoranda leaves will be in convenient position for writing thereon, and when the book is reversed for writing on the other side of the leaves, the other memoranda leaf will be in like position for writing thereon.

My invention provides further a device of the kind described which is simple, cheaply made, easily operated, and efficient in operation.

The novel features of my invention are hereinafter fully described and claimed.

In the accompanying drawing, which illustrates the preferred embodiment of my invention, as applied to two types of books,

Fig. 1, is a perspective view of a type of book, commonly used by stenographers, and having the covers swinging from the upper end of the book, provided with my improvement.

Fig. 2 is another perspective of the book shown in Fig. 1, the covers being nearly closed.

Fig. 3 is an elevation of the book shown in Figs. 1 and 2, showing one of the covers turned back.

Fig. 4, is a perspective of a book, of the type having the leaves swinging from the side edges, provided with my improvement, a portion of one cover being broken away.

Similar reference characters designate similar parts in the different views.

Referring to Figs. 1 to 3, 1 designates the two covers of the book, 2 the usual leaves thereof, and 3 and 4 two memoranda leaves embodying my improvement and disposed respectively adjacent to the covers 1.

Each of the leaves 3 and 4 is provided with a hinged memoranda portion adapted to be swung to a position projecting outside the edges of the other leaves, and comprising, preferably, a tongue 5 cut from the body of the leaf, and hinged thereto on a longitudinal axis so as to be swung to a projecting position, as shown in Figs. 1, 2 and 3, and, when not in use being adapted to be swung to a position wholly inside the edges of the leaves, as shown by the leaf 3, Fig. 1.

In the type of book shown in Figs. 1 to 3, the axes of the tongues 5 are respectively adjacent to opposite longitudinal edges of the leaves. This construction enables one tongue 5 to be disposed at the right side of the book, when extended, when one side of the leaves 2 is being written on, and when the other side of the leaves 2 is being written on, the book being reversed in the usual manner, the other tongue 5 will be disposed at the right, when extended.

In the type of book shown in Fig. 4, the memoranda leaves 6 and 7, corresponding to the leaves 3 and 4, have the tongues 5 both hinged to the leaves adjacent to the outer longitudinal edges thereof, so that in the use of the book each tongue will project to the right, when the book is reversed for writing on both sides of the leaves.

In the operation of my invention with both types of books shown, the tongues 5 of the rear leaves 4 and 7 are swung to the projecting position, at the right, while the front sides of the leaves are being written on. The writer, from time to time may make such entries on the memoranda tongues as he may desire, and this can be done without having to move the writing hand to the right but a short distance from the normal writing position. Thus while busy taking dictation or reporting, he can, without loss of time, enter memoranda on the memoranda tongues. When writing is

finished, the tongues 5 can be folded into the book for future reference. By having the hinged portions of the tongues 5 adjacent to the edges of the leaves, relatively weak 5 connections exist between the tongues and leaves, which, however, are strong enough for the temporary purpose of the book, but which enable the memorandum tongues to be readily detached for filing away, after 10 the book has been filled and is no longer used.

I do not limit my invention to the structures shown and described, as many modifications, within the scope of the appended 15 claims, may be made without departing from the spirit of my invention.

What I claim is:—

1. A book of the kind described having one of its leaves provided with a memoranda 20 tongue having connection with the leaf at

the inner side of and spaced from one edge of the leaf and cut from the body of the leaf and having one end edge and its side edges free, and adapted to be swung to and from a position projecting outside of the 25 edges of the other leaves.

2. A book of the kind described having two of its leaves, which are respectively adjacent to the covers of the book, each provided with a memoranda tongue cut from 30 the body of the leaf and adapted to be swung to and from a position projecting outside the edges of the other leaves, the axes of the tongues being respectively at the inner side of and spaced from opposite 35 edges of the leaves.

In testimony whereof, I have signed my name to this specification.

CLARK A. THARP
